UNITED STATES PATENT OFFICE.

JOHN A. HILLERICH, OF LOUISVILLE, KENTUCKY, ASSIGNOR TO HILLERICH & BRADSBY COMPANY, A CORPORATION OF KENTUCKY.

BAT.

1,213,370.

Specification of Letters Patent. Patented Jan. 23, 1917.

Application filed October 9, 1915. Serial No. 55,018.

To all whom it may concern:

Be it known that I, JOHN A. HILLERICH, a citizen of the United States, residing at Louisville, in the county of Jefferson and State of Kentucky, have invented certain new and useful Improvements in Bats, of which the following is a specification.

The present improvement relates to handles for golf clubs, base ball bats, tennis rackets, hockey sticks and other sporting goods for which this construction is suitable.

It relates to the invention set forth in my Patent 1,110,487, dated September 15, 1914, and is an improvement thereon, being especially directed to the application of a cork handle covering to shafts or handles of relatively small diameter, in such manner as to give an enlarged or cushioned (or both) foundation for the cork grip covering of such handles.

With such objects in view the invention consists in the parts and combinations thereof hereinafter set forth and claimed.

In order to make the invention more clearly understood I have shown in the accompanying drawings means for carrying the same into practical effect without limiting my improvements, in their useful applications, to the particular construction which, for the purpose of example, has been made the subject of illustration.

In said drawings—Figure 1 is a side view of a shaft for a golf club or bat embodying the invention. Fig. 2 is a longitudinal section of the handle portion of the same, on line II—II of Fig. 1, on a larger scale. Fig. 3 is a plan view of the sheet or layer of cork before it is applied to the handle. Fig. 4 is a side view of a portion of the handle illustrating the application thereto of the enlarging and cushioning base over which the sheet of cork is thereafter applied. Fig. 5 is a cross section of the handle illustrating the manner of applying the cork thereto under tension. Fig. 6 is a similar view of the completed handle. Figs. 7 and 8 are partial cross sections on an exaggerated scale illustrating the sheet of cork before and after its edges have been brought together to form the joint.

Referring to the drawings 1 indicates the shaft of a golf stick, and 2 the handle thereof.

3 is a sheet or layer of cork of sufficient length to form the necessary grip, and

shaped at its longitudinal edges, according to the contour of the handle, so that when it is first applied around the handle in proper position its said longitudinal edges will not quite meet. This sheet of cork is preferably about one-sixteenth of an inch in thickness, and a convenient length for the same is about twelve inches.

4 indicates the enlarging and preferably cushioning foundation of the cork sheet. 65 This foundation consists preferably of a strip of woolen listing wound upon the handle portion, as indicated in Fig. 4. This foundation may however be of leather, and it may be in the form of a strip wound spirally or it may in the form of a sheet passing once around the handle. Before the said foundation 4 is applied, I first give to the handle, and to the inner side of the foundation material if desired, a coating of 70 water-proof fish glue cement, after which the foundation strip or sheet is applied tightly to the handle, and allowed to dry in such condition. After the said foundation is dry I apply to the same an exterior coating 75 of such cement or glue and apply a similar coating to the inner side of the cork sheet. Then a thread or cord *c* is wound around the cork sheet in such manner as to compress the same and increase its width, and this compression is continued until the edges of the cork sheet are brought firmly together. The cement is then allowed to become thoroughly dry and the cord *c* is removed. The inner surface or skin of the cork sheet is then coincident with and practically integral with the extreme exterior surface of the said foundation, and the outer portions of the cork are in a state of tension, which gives great firmness to the handle and prevents the sheet from becoming detached at any point from the handle. The tension of the cork sheet is evenly distributed from end to end of the same, by reason of the preliminary shaping of the sheet and the manner in which it was applied to the bat handle. The longitudinal edges 5 of the cork sheet may be shaped to form a butt joint, as indicated at 6 in Fig. 5; or they may be shaped to form a lap joint as indicated at 7 in Figs. 7 and 8.

The thread or cord *c* is applied by a winding machine, while the operator holds the cork sheet in proper position curled around the bat handle, proper tension being maintained upon the cork to flatten out or spread

or stretch the cork as may be necessary to make a perfect joint and leave the cork in its final stretched condition after it has dried and the cord has been removed.

5 Any variation in taper or contour from the cylindrical which the handle portion of the club may have is allowed for by variations in the width of the sheet of cork, so that all parts of the same are substantially 10 equally stretched when the edges of the sheet have been brought into proper contact, so that an exact and durable joint between said edges of the cork sheet is produced. The cork sheet is originally of sufficient thickness to allow of its being spread and thinned until the required joint has been made, and after drying every part of the cork is so fixedly and permanently united that the tension set up in the cork 15 cannot cause any tearing or splitting after the cord *c* has been removed. After the cork has been applied as described, and the bat dried, the same may be put in a lathe and the end edges of the cork sheet finished to a 20 feather edge, as indicated at 8 in Fig. 2, so as to prevent any pushing up and roughing of the cork at these points.

25 As a result of the described improvements, the advantages of cork in giving a good grip, absorbing shock, etc., are made available in practical and durable form. Moreover the diameter of the relatively small shaft is increased to allow of a better grip upon the same, and the cork is cushioned so as to give a resilient body or surface, which adds materially to the firmness of the grip

which may be had upon the handle and adds to the shock absorbing quality of the thin cork sheet, and to the accuracy with which the club can be directed and controlled.

40

While the middle portion of the cork sheet passes around and is secured to the described cushioned enlargement, the end portions of said sheet extend in each direction a little beyond said foundation and are applied and secured directly to the wood of the shaft at each end of said foundation.

45

What I claim is:

1. A handle for a base ball bat, tennis racket, hockey stick, and other sporting goods, for which this construction is suitable, covered with a sheet of cork under tension and secured in place by adhesion, and having an enlarging and cushioning foundation applied under the cork and firmly attached to the handle and to the inner side of the cork.

50

2. A handle for a base ball bat, tennis racket, hockey stick, and other sporting goods, for which this construction is suitable, covered with a sheet of cork under tension, and having an enlarging and cushioning foundation applied under the cork and firmly attached to the handle and to the inner side of the cork, the end portions of 55 said cork extending beyond the said foundation and being applied and secured by adhesion directly to the handle.

60

In testimony whereof I affix my signature hereto.

JOHN A. HILLERICH.
